UNITED STATES PATENT OFFICE

ANDREW L. HENRY, OF INDIANAPOLIS, INDIANA, ASSIGNOR TO TROLLEY SHOE WHEEL COMPANY, OF INDIANAPOLIS, INDIANA, A CORPORATION OF INDIANA

TROLLEY SHOE

Application filed May 2, 1930. Serial No. 449,332.

This invention relates to trolley shoes, with particular attention to the mechanism for aiding the shoe during the reverse travel of the car.

5 An object of the invention is to provide a trolley shoe which will provide better contact with the trolley wire during the reverse motion of the car, and which will at the same time eliminate the possibility of pulling the 10 trolley pole forward when the car is in reverse motion, which would buckle the pole and endanger the over-head equipment.

A further object of the invention is to provide a sliding contact trolley shoe which will 15 operate in a reverse motion without being "led", and which will back without manual assistance, automatically bringing into play a combination wheel and slide for backing.

Referring to the accompanying drawings 20 which are made a part hereof and on which similar reference characters indicate similar parts,

Figure 1 is a side elevation of the trolley shoe showing the position occupied when the 25 car is moving forward,

Figure 2, a side elevation of the shoe showing its position when the car is in reverse,

Figure 3, a perspective view of a detail of the shoe, and

30 Figure 4, a perspective view of another detail of the shoe.

In the drawings, numeral 10 indicates a trolley harp having its upper end bifurcated, and having a spider 11 pivoted therein on 35 pin 12. One arm of the spider 11 has bifurcations 13, between which is pivoted a lug 14 on the under side of the trolley shoe holder 15, through which lug 14 and the bifurcated arm 13, is placed pin 28. The holder 15 has 40 a grooved tread 16 secured on its upper side. This tread 16 is preferably secured to the holder 15 by means of the cotter keys 17. When the tread becomes worn, it may thus be removed and a new one fastened to the holder by the simple operation of cutting the two cotter keys 17, removing the tread 16, and replacing both it and the keys.

In order to provide better electrical contact between the shoe and the harp, a wire 18 of high current carrying material is secured

to the side of the holder at 19, and to the side of the harp at 20. This shunt wire gives greater current carrying capacity, and prevents the burning of the pins 12 and 28 or their eyes, by the current which would arc 55 across the oil films therein.

The arm 21 of the spider 11 has a roller 22 mounted on its upper end. This roller 22 forms a back-up wheel by rolling against the wire 23 when the car is in reverse motion. 60 The end of the harp 10 has a stop shoulder 24 against which a lug 25 on the spider 11 contacts to limit the upward movement of the spider. A pin or lug 26 on the spider 11 contacts with a shoulder 27 just beneath 65 the lower end of the harp to limit the downward movement of the spider. The spider also carries a stop pin 29 which contacts with shoulder 30 on the holder 15. A shoulder 31 on the holder 15 contacts with a side of arm 70 13 on the spider 11 at 32 to limit any possible counterclockwise rotation of the shoe. The pin 12 on which the spider is pivoted, and the pin 28 on which the holder is pivoted, are provided with oil holes 33 and 34, as shown 75 in Figure 1.

When the car is moving forward, the friction and pull tend to force tread 16 back, and this holds the trolley in position as in Figure 1, parallel with the wire 23. The backward 80 pull on the tread 16 and the holder 15 as a unit, pulls back on pin 28 which places a horizontal backward pull on the bifurcated arm 13, holding the spider 11 so that stop lug 26 is against shoulder 27, and arm 21 is as far down 85 as possible, and wheel 22 in that arm 21 is well below the wire 23.

When the car starts to back the reverse pressure is applied, and the friction and push of the backing car push the unit consisting of 90 tread 16 and holder 15 horizontally forward. The upward trolley tension on the trolley pole and harp 10 holds the tread 16 flat and in full contact with the wire 23 as the backing movement pushes the unit forward. As 95 tread 16 and holder 15 move forward, pin 28 comes forward with them, being pulled by the lug 14 through which it runs. Pin 28 also extends through the bifurcations of arm 13, and so pulls arm 13 forward, and as arm 100

13 progresses forward, the spider 11 pivots on the axis pin 12, causing arm 21 to move upward, carrying wheel 22 up until it comes against wire 23.

5 The pushing pressure and friction move the tread 16 forward, but it remains in full contact with the wire 23, and the spider 11 is held forward as explained, keeping wheel 22 tight against wire 23, and enabling the car to back on a revolving wheel, which removes 10 any possibility of buckling the trolley pole while backing.

When the car starts forward, the pressure is again reversed, and becomes a pull which 15 slides tread 16 back horizontally to the normal position in Fig. 1. As tread 16 and tread holder 15 come back to normal position, pin 28 is pulled back, as is also arm 13, and arm 20 21 moves downward again as the spider 11 pivots on axis pin 12, and the wheel 22 is lowered to normal.

The pin 28 enables the horizontal movements of the tread and holder to take place and still have tread 16 continuously in full 25 contact with the wire 23, delivering a full current supply at all times.

It will be obvious to those skilled in the art that various changes may be made in my device without departing from the spirit of the 30 invention, and therefore I do not limit myself to what is shown in the drawings and described in the specification, but only as indicated in the appended claims.

Having thus fully described my said invention, what I claim as new and desire to 35 secure by Letters Patent, is:

1. A trolley shoe comprising a harp, a spider pivoted to the harp, said spider having two arms diverging upwardly from the 40 pivotal point with respect to said harp, a frame pivotally mounted in one of the arms, said frame carrying a trolley contact shoe detachably secured thereon, the other arm of the spider carrying a roller for contact 45 with the trolley wire when the car is moving backwards, substantially as set forth.

2. A trolley shoe comprising a harp, a spider pivoted in the harp, said spider having two diverging arms extending from the 50 point of rotation with respect to said harp, a frame pivotally mounted in one of the arms, said frame carrying a trolley contact shoe detachably secured thereon, the other arm of the spider carrying a roller movable to contact 55 with the trolley wire when the car is moving backwards, and a separate flexible conduit attached to the harp and to the said frame to provide good electrical contact between the harp and the shoe to avoid arcing and burning out lubricant from the bearings on which the frame and spider pivot, substantially as set forth.

3. A trolley shoe comprising a harp, a spider pivotally attached to the harp, said 60 spider having a pair of arms, one extending

upwardly on each side of the pivotal point, a frame pivoted in one of the arms, said frame carrying a trolley contact shoe, the free end of the other arm of the spider carrying a roller, said roller being brought into contact 70 with the trolley wire when the car is moving backwards, the harp being provided with stop lugs for limiting the movement of the spider beyond a predetermined distance in either direction, substantially as set forth. 75

4. A trolley shoe comprising a harp, a spider mounted in the harp, a pair of arms on the spider, a frame mounted on one arm of the spider, said frame having a trolley tread mounted thereon, a wheel carried by 80 the other arm of the spider, said tread frictionally engaging the trolley wire to hold the said wheel out of engagement with the trolley wire when the car is moving forward and said tread moving horizontally forward to rotate 85 the spider on its pivot to move the said wheel into engagement with the trolley wire when the car moves backward, substantially as set forth.

5. A trolley shoe comprising a harp, a spider mounted in the harp, a pair of arms on the spider, a frame mounted on one arm of the spider, said frame having a trolley tread mounted thereon, a wheel carried by 90 the other arm of the spider, said tread frictionally engaging the trolley wire to hold the said wheel out of engagement with the trolley wire when the car is moving forward and said tread moving horizontally forward to rotate 95 the spider on its pivot to move the said wheel into engagement with the trolley wire when the car moves backward, substantially as set forth. 100

6. A trolley shoe comprising a harp, a spider mounted in the harp, a pair of arms on the spider, a frame mounted on one arm of the spider, said frame having a trolley tread mounted thereon, a wheel carried by 110 the other arm of the spider, said tread frictionally engaging the trolley wire to hold the said wheel out of engagement with the trolley wire when the car is moving forward and said tread moving horizontally forward to rotate 115 the spider on its pivot to move the said wheel into engagement with the trolley wire when the car moves backward, cooperating stops and abutments on said spider and said harp to limit rear movement of the tread when the 120 car is moving forward, substantially as set forth. 125

7. A trolley shoe comprising a harp, a spider pivotally mounted in the harp, a frame pivoted on the spider, said frame carrying a contact tread in slidable contact with and substantially parallel to the trolley wire during both forward and backward movement of the car, and a roller on the spider movable to engage the trolley wire only during back- 130

ward movement of the car, substantially as set forth.

8. A trolley shoe comprising a harp, a spider pivotally mounted in the harp, a frame pivoted on the spider, the frame having a contact tread mounted thereon said tread being in engagement with and parallel to the trolley wire during both forward and backward movement of the car to maintain good electrical contact between the harp and the wire, and a roller positioned in the spider and movable to engage the trolley wire to prevent buckling of the trolley pole when the car is moved backward, substantially as set forth.
- 15 In witness whereof, I have hereunto set my hand at Indianapolis, Indiana, this 29th day of April, A. D. nineteen hundred and thirty.

ANDREW L. HENRY.
